UNITED STATES PATENT OFFICE.

JOHN AYRES, OF PORTLAND, OREGON, ASSIGNOR TO OREGON RAFTING COMPANY, OF PORTLAND, OREGON, A CORPORATION OF OREGON.

LOG RAFT.

SPECIFICATION forming part of Letters Patent No. 715,939, dated December 16, 1902.

Application filed September 25, 1902. Serial No. 124,821. (No model.)

To all whom it may concern:

Be it known that I, JOHN AYRES, a citizen of the United States, residing at Portland, county of Multnomah, State of Oregon, have 5 invented certain new and useful Improvements in Log Rafts; and I do hereby declare the following to be a full, clear, and exact description of the same.

My invention relates to that class of rafts 10 composed of logs or timbers so built up and fastened together as to adapt the structure to be transported on the water, and especially to be carried on long voyages on the ocean, with a view to being broken up and its logs 15 or timbers sold at the place of destination. In rafts of this nature it is the practice to form the logs or timbers into an immense structure, usually cigar-shaped, and to bind the logs or timbers together by various means, which in- 20 clude encircling chains at frequent intervals, and to dispose in the raft other chains by the strain on which in towing the raft is held together. Heretofore these interior chains have been so disposed that while the strain of tow- 25 ing pulls together and tightens the raft in its after part the forward part of the raft, having nothing but the resistance of the water to oppose the forward pulling strain on the after part, tends to slacken up and loosen, so 30 that considerable difficulty is experienced in keeping the forward part of the raft tight and compact, and it is found after the voyage is well under way that while the raft is tight enough aft it is quite loose forward.

35 The object of my invention is to overcome this difficulty by providing such an arrangement and connection of tow-chains and tightening-chains as will cause the two ends of the raft under the strain on the tow-chain to 40 tighten or pull together against each other—that is to say, the strain on each end will be toward the center—thereby keeping both ends of the raft tight.

To this end my invention consists in a tow- 45 chain through the raft, said chain being made in sections connected by a pulley-block in such manner that the strain of towing will pull the sections centrally in opposite direc- 50 tions, and "diagonal" or "herring-bone" chains in the forward and after portions of the raft secured interiorly to the tow-chain

sections and exteriorly to the raft, said diagonal or herring-bone chains being relatively disposed to strain and tighten the two ends of the raft together under the strain of towing. 55

Referring to the accompanying drawings, Figure 1 is a horizontal central sectional plan of my raft, a portion of the middle being left in full plan. Fig. 2 is a view of the forward end of the raft sectioned as shown in Fig. 1. 60 Fig. 3 is a view of the after end of the raft not sectioned as in Fig. 1, but complete. Fig. 4 is a detail view showing the block connection between the two sections of the tow-chain. Fig. 5 is a sectional view of block D. 65 Fig. 6 is a detail view showing the connection between a herring-bone chain and an encircling chain.

A is the raft. It is composed of logs or timbers laid up suitably to about the shape shown 70 or any other shape which in such rafts may be found practicable.

B is the forward section of the tow-chain. This in its best form is doubled on itself and lies in about the middle plane of the forward 75 part of the raft. The end b, with which the tow connection is made, issues from the forward end of the raft slightly below the middle, while the other end b' lies in the middle plane just within the forward end and is connected with the forward diagonal or herring-bone chains C. In building the raft when the structure is nearing the horizontal central plane the end b of chain B is laid in, and when the middle plane is reached the end 80 b' is laid in forwardly in said plane, and thereby the two sides of said chain are kept separate and free from chafing. The bight or inner bend of chain-section B runs through a block D, which is secured to the after section 85 E of the tow-chain. This chain in its best form is a single chain and passes out aft through the raft and is thence carried upwardly to the top of the raft, and its end e is secured to one of the encircling chains. To 90 this chain E are secured the after diagonal or herring-bone chains F. The herring-bone chains C and F may be in any suitable number, and each consists of a single chain suitably connected at its middle—say by a "clove" 95 hitch—to the chain B or the chain E, as the case may be, and its ends are thence carried 100

out diagonally in an endwise direction to the raft exterior and are there secured in suitable manner to the encircling chains G, which lie in the cross-sectional planes of the raft. These 5 encircling chains are at frequent intervals, as shown, and the connection of the herring-bone chains therewith is here shown as consisting of a removable plate H on a yoke h on the end of each chain and which form sockets embracing the encircling chains. By the removal of the plates H the connection of the chains is readily broken when the raft is to be broken up.

10 I is a stop-chain secured to and extending 15 between the two sides of chain B forward of the block D.

15 It will now be seen that the strain of towing applied to the end b of the forward section B of the tow-chain will, through the 20 block connection at D, pull forward on the after chain-section E, and thereby through the after herring-bone chains F tighten up the after end of the raft, and at the same time the strain of towing will pull back on the portion b' of the forward chain-section B, and 25 thereby through the forward herring-bone chains C will pull back on and tighten up the forward end of the raft, the two ends of the raft thus being strained together and kept 30 tight positively under the strain of towing. In towing thus by the forward end the stop-chain I, which is run diagonally, as shown, is slack enough to not interfere with the proper running of chain B; but in case the occasion 35 should arise when the raft should have to be towed from the other end the end e of the after tow-chain section E is released from the encircling chain and is taken hold of to tow by, and in this case the stop-chain I serves 40 to hold chain B properly, so that its free end b will not be pulled through. Such towing by the rear end will, however, be only in case of emergency, and if resorted to the two sections B and E will act only as a straight 45 through tow-chain.

Having thus described my invention, what I claim as new, and desire to secure by Letters Patent, is—

1. In a log raft, the combination of a tow-chain extending through the length of the 50 raft and made in separate sections, a pulley-block between and connecting said sections, said block and chains being relatively arranged to cause the strain of towing applied 55 to one of said sections to effect a pull on said sections in opposite directions toward the center of the raft, and diagonal chains in the forward and after portions of the raft secured interiorly to the tow-chain sections and exteriorly to the raft, and relatively disposed to apply the opposite strains on the tow-chain sections to tightening the ends of the raft together.

2. In a log raft, the combination of a tow-chain 60 extending through the length of the raft and made in separate sections, a pulley-block between and connecting said sections,

said block and chains being relatively arranged to cause the strain of towing applied to one of said sections to effect a pull on said sections in opposite directions toward the center of the raft, encircling chains in the cross-sectional planes of the raft, and diagonal chains in the forward and after portions of the raft secured interiorly to the tow-chain 75 sections and exteriorly to the raft-encircling chains, and relatively disposed to apply the opposite strains on the tow-chain sections to tightening the ends of the raft together.

3. In a log raft, the combination of the doubled section of the tow-chain in the forward portion of the raft, the single section of the tow-chain in the after portion of the raft, the block connected with the after tow-chain section, through which block the bight of the 80 forward tow-chain section runs, and the herring-bone chains in the forward and after portions of the raft, secured interiorly to the tow-chain sections and exteriorly to the raft, whereby the ends of the raft are strained and 85 tightened together in towing from the forward end.

4. In a log raft, the combination of the doubled section of the tow-chain in the forward portion of the raft, the single section of the 90 tow-chain in the after portion of the raft, each section having an end issuing through the raft end to the exterior, the block connected with the after tow-chain section, through which block the bight of the forward tow-chain section runs, the herring-bone chains in the 95 forward and after portions of the raft secured interiorly to the tow-chain sections, and exteriorly to the raft, whereby the ends of the raft are strained and tightened together in 100 towing from the forward end, and the stop-chain connecting the two sides of the forward tow-chain section whereby the towing may be done if necessary by the projecting end of the after tow-chain section.

5. In a log raft, the combination of the doubled section of the tow-chain in the forward portion of the raft, the single section of the tow-chain in the after portion of the raft, the block connected with the after tow-chain section, through which said block the bight of the forward tow-chain section runs, the herring-bone chains in the forward and after portions of the raft, secured interiorly to the tow-chain sections, and the encircling chains about 115 the raft, and to which the herring-bone chains are exteriorly connected, whereby the ends of the raft are strained and tightened together in 120 towing from the forward end.

6. In a log raft, the combination of the doubled section of the tow-chain in the forward portion of the raft, the single section of the tow-chain in the after portion of the raft, each section having an end issuing through the raft end to the exterior, the block connected with the after tow-chain section, through which block the bight of the forward tow-chain section runs, the herring-bone chains in the 125 forward and after portions of the raft secured 130

interiorly to the tow-chain sections, the encircling chains about the raft and to which the herring-bone chains are exteriorly connected, whereby the ends of the raft are strained and 5 tightened together in towing from the forward end, and the stop-chain connecting the two sides of the forward tow-chain section, whereby the towing may be done if necessary, by

the projecting end of the after tow-chain section.

In witness whereof I have hereunto set my hand.

JOHN AYRES.
